WEIGHT INDICATING DEVICE

James A. Endicott, McPherson, Kans.

Application March 2, 1935, Serial No. 9,009

7 Claims. (Cl. 73—31)

This invention relates to new and useful improvements in weight indicating devices.

In the drilling of wells, particularly for oil and gas, the drilling mud is pumped from a slush pit 5 into the drill stem extending into the well. The lower end of the drill stem carries a drill bit and the mud being pumped into the stem washes the cuttings from the bottom of the hole. The drilling mud and cuttings escape upwardly between the drill stem and formation being cut and are conveyed back to the slush pit. The mud being used must be heavy enough to prevent loss of returns and also to prevent the mud entering the formation. Also the weight of the mud 10 varies depending on the particular formation being drilled.

One object of the invention is to provide an improved device, whereby the weight of the drilling mud, or similar fluid, being pumped may be positively ascertained.

20 An important object of the invention is to provide improved indicating means connected with a suction pump which is handling drilling fluid whereby the variation in the suction of the pump caused by the variation in the weight of the drilling fluid will be indicated, thereby showing the actual weight of the fluid being pumped.

A further object of the invention is to provide a piston actuated by the suction of a pump, said piston being connected with and operating any 30 indicator, whereby the variation in the suction of said pump is positively indicated.

A construction designed to carry out the invention will be hereinafter described, together with other features of the invention.

35 The invention will be more readily understood from a reading of the following specification and by reference to the accompanying drawings, in which an example of the invention is shown, and wherein:

40 Figure 1 is a side elevation of a device, constructed in accordance with the invention, and connected with a suction pump.

Figure 2 is an enlarged side elevation of the device.

45 Figure 3 is a longitudinal vertical, sectional view of the device.

Figure 4 is a plan view.

Figure 5 is an isometric view of the pitman and its connection, and

50 Figure 6 is an isometric view of the weight.

In the drawings, the numeral 10 designates a vertical cylinder which has a piston 11 slidable therein. The bottom 12 of the cylinder is provided with an opening 13 which is internally

screw-threaded to receive a valve 14. A collar 15 surrounds the opening 13 and is externally screw-threaded to receive the upper end of a short pipe 16. The lower end of the pipe is connected with the suction line 17 of a suction pump 18. The pump may be of any desired construction.

The piston 11 is provided with a vertically extending piston rod 19 which extends upwardly through a stuffing box 20 in the top of the cylinder 10. The upper end of the rod is threaded into a collar 21 which has a clevis 22 made integral with its upper end. A laterally extending pitman 23 has one end pivoted in the clevis 22 on a pin 24. The other end of the pitman is pivoted between ears 25 on a pin 26. The ears 25 are formed on the upper end of a vertical standard 27 which has its lower end telescoping in a vertical pipe 28, whereby said standard may be lowered and raised with relation to the pipe 28. A set screw 29 holds the standard in various adjusted positions. The pipe 28 has its lower end welded or otherwise secured to a horizontal platform or support 30 which extends outwardly from one side of the cylinder 10, being secured to said cylinder in any suitable manner.

From the above, it is obvious that upon the suction stroke of the pump, the valve 14 in the bottom of the cylinder will be drawn downwardly to an open position. This permits the suction of the pump to act upon the piston 11 to pull the same downwardly (dotted lines Figure 3) within the cylinder. Downward movement of the piston will pull the piston rod 19 downwardly and swing the pitman, which will pivot on the pin 26. The clevis 22 may be provided with slots 24' to compensate for the swinging of said pitman. It is obvious that if a heavier drilling mud, or fluid, is being pumped through by the pump 18, a greater suction is present in the suction line 17, which will create more pull on the piston 11 and cause it to move downwardly a further distance in the cylinder. If the fluid being pumped is comparatively light, less suction is present in the line 17 and the piston is moved a lesser distance. Thus, it will be seen that the weight of the fluid controls the suction of the pump and this suction moves the piston in proportion thereto, the movement of the piston controlling the swinging of the pitman 23. It is noted that the suction static head is maintained substantially constant, whereby the pressure of the pump is unaffected by the static head. Also, the speed of the pump is also maintained sub-

stantially constant, whereby the speed of the pump does not change with a change in the consistency of the material.

For indicating the weight of the fluid being pumped, the pitman 23, has a weight 31 slidably mounted thereon. The weight is held in a fixed position on said pitman by a set screw 32 and is provided with a head 33 at its lower end. When the piston 11 is in a raised position (Figure 3) and the pitman is swung to a horizontal position, the head 33 of said weight is directly above a diaphragm 34. The diaphragm is mounted in the usual case 35 which is connected with a pressure chamber 36. The chamber comprises a U-shaped pipe 37 and the horizontal portion of the pipe 37 is mounted within a casing 38 supported by the support or platform 30. One vertical leg of the U-shaped pipe carries the diaphragm case 35 while the other leg 20 of the pipe 37 has a gauge 39 or other suitable indicator mounted thereon. This gauge may be of any suitable type which is actuated by fluid pressure. The pressure chamber may have fluid or liquid entered therein and it is obvious that 25 by depressing the diaphragm, the gauge will be actuated.

Thus, when the suction of the pump moves the piston 11 a certain distance within the cylinder 10, the pitman is swung to apply a certain 30 pressure on the diaphragm 34 through the weight 31, whereby such pressure is indicated by the gauge 39. Variation in the suction line 17, varies the movement of the piston and a greater or less pressure is exerted on the diaphragm to cause 35 various indications by the gauge. Since the suction in the line 17 is positively controlled by the weight of the fluid being pumped, it is obvious that the exact weight of the fluid is indicated by the gauge 39. The vertical adjustment 40 of the standard 27 within its supporting pipe 28, provides for varying the swing of the pitman. The valve 14 at the bottom of the cylinder 10 is so arranged that upon the suction stroke of the pump, it is pulled open, but upon 45 the exhaust stroke of the pump, the valve is seated so as to prevent fluid entering the cylinder beneath the plunger.

It is pointed out that the gauge will positively indicate the weight of the fluid being pumped 50 upon each stroke. Thus, the operator will at all times be aware of this weight and therefore, if the fluid becomes too thin or too thick, he can quickly remedy the trouble. By maintaining the fluid at its proper weight, depending 55 upon the conditions under which drilling is being done, the danger of the well "blowing in" is eliminated. This is especially true in gas wells. Further, since the weight of the fluid must vary according to the formation being drilled, it is 60 obvious that the drilling operation can be greatly speeded up for no time is necessary for weighing the fluid before pumping. The pump is started and the gauge immediately registers the weight of the fluid. The operator can then increase or decrease the weight of the fluid until 65 the indicator of the gauge is proper.

It is pointed out that although the device has been described as indicating the weight of drilling fluid, it can be used in combination with any 70 suction pump and may be utilized for indicating the weight of any fluid such as cement slurry, or the like.

What I claim and desire to secure by Letters Patent, is:

1. In a gauge of the type described, a cylinder connected with a suction line, a piston movable within the cylinder and actuated by the suction in said line, a swinging member connected with the piston and arranged to be swung thereby, a pressure chamber, an indicator actuated by the pressure in the chamber connected with one end of said chamber, a diaphragm at the other end of said chamber arranged to be engaged and actuated by the swinging member, whereby when said member is swung the diaphragm is actuated to increase the pressure within the chamber to operate the indicator, whereby variations in the suction in said line are indicated, thereby indicating the weight of the fluid being drawn through said line. 5

2. In a gauge of the type described, a pressure indicator, movable means actuated by a source of suction, and means connected with and actuated by said movable means for applying pressure to said indicator, whereby said pressure indicator is actuated by the suction. 10

3. In a gauge of the type described, a pressure indicator, means for transforming a source of suction into a pressure, and means for applying the pressure to said indicator, whereby said indicator is actuated by said suction. 15

4. In a gauge of the type described, a pressure indicator, movable means connected with and actuated by a source of suction, whereby variations in said suction vary the movement of said means, a swinging member connected with said means, and a pressure chamber connected with the pressure indicator and with said swinging member, whereby movement of said member will vary the pressure to said indicator. 20

5. In a gauge of the type described, a cylinder connected with a suction line, a piston movable within the cylinder and actuated by the suction in said line, a pressure indicator, a pressure chamber having one end connected with the indicator for actuating the same, and means connected with and actuated by the piston for varying the pressure in the chamber, whereby the indicator is actuated in proportion to the movement of the piston. 25

6. In a gauge of the type described, a cylinder connected with a suction line, a piston movable within the cylinder and actuated by the suction in said line, a pressure indicator, a pressure chamber having one end connected with the indicator for actuating the same, and a swinging member connected with and actuated by the piston for varying the pressure in the chamber, whereby the indicator is actuated in proportion to the movement of the piston. 30

7. In a gauge of the type described, a cylinder connected with a suction line, a piston movable within the cylinder and actuated by the suction in said line, a pressure indicator, a pressure chamber having one end connected with the indicator for actuating the same, means connected with and actuated by the piston for varying the pressure in the chamber, whereby the indicator is actuated in proportion to the movement of the piston, and a check valve mounted between the suction line and the piston. 35
